(57) **CLAIM**

The ornamental design for a set of fork, spoon and knife, as shown and described.

DESCRIPTION

FIG. 1 is a front perspective view of the knife of the set, shown separately for ease of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 7;

FIG. 10 is an enlarged detail view of area 10 in FIG. 8;

FIG. 11 is a front perspective view of the fork of the set, shown separately for ease of illustration;

FIG. 12 is a bottom perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an enlarged detail view of area 19 in FIG. 17;

FIG. 20 is an enlarged detail view of area 20 in FIG. 18;

FIG. 21 is a front perspective view of the spoon of the set, shown separately for ease of illustration;

FIG. 22 is a bottom perspective view thereof;

FIG. 23 is a front view thereof;

FIG. 24 is a rear view thereof;

FIG. 25 is a left side view thereof;

FIG. 26 is a right side view thereof;

FIG. 27 is a top view thereof; and,

FIG. 28 is a bottom view thereof.
